UNITED STATES PATENT OFFICE.

RICHARD SPRINGBORN, OF CLEVELAND, OHIO.

CUSHIONING DEVICE.

1,278,246.

Specification of Letters Patent. Patented Sept. 10, 1918.

Application filed February 20, 1918. Serial No. 218,354.

To all whom it may concern:

Be it known that I, RICHARD SPRINGBORN, citizen of the United States, residing at Cleveland, in the county of Cuyahoga and State of Ohio, have invented certain new and useful Improvements in Cushioning Devices, of which the following is a specification.

This invention relates to cushioning devices, or in other words, to devices for cushioning or offering yielding resistance to the movement of parts. The object of the invention is to provide an improved device of this kind which is of simple form and can therefore be made cheaply; whose active part may be of cast metal, thereby avoiding the necessity of tempering operations; whose amount of yield may be definitely limited by the construction of the device itself; and which device is also capable of use in a wide variety of ways and is therefore adaptable for utilization in many different forms of device. Further objects of the invention are in part obvious and in part will appear more in detail hereinafter.

Figure 1 illustrates a sectional elevation through one form of device embodying the invention; Fig. 2 is a plan view thereof, with the upper member omitted; Fig. 3 is a sectional view, corresponding to Fig. 1, and illustrating a modification; and Fig. 4 is a longitudinal sectional view showing one form of fitting embodying the invention.

My improved cushioning device comprises essentially three members; to wit, a compressible ring or annulus and two coöperating seat members therefor. The ring or annulus may take several forms, for example, in Fig. 1 the ring 1 illustrated is of substantially triangular cross section, its inner portion having the wide surface 2 and its outer portion having the narrower surface 3 at the angle of the triangle. It is therefore provided with upper and lower inclined or conical faces 4 and 5. Said ring coöperates with two seat members 6 and 7, which are also circular in form and one or both of which are provided with inclined substantially conical seats or seat faces 12 to coöperate with the seat faces 4 and 5 of the ring. Members 6 and 7 may be suitably connected or arranged so that their movement relative to each other is confined to movement along their common axis, lateral movement relative thereto being prevented. This result may be secured by several ways, for ex-

ample by providing one member, say member 7, with a projection 8 working in a guiding opening 9 in the other member, or, as shown in Fig. 3, by confining both members 6^a and 7^a in a surrounding cylinder 10.

The ring 2 is split at one point in its circumference, for example by sawing it radially to produce the narrow slot 11. This slot enables the ring to be collapsed or compressed until the neighboring end surfaces at the sides of the slot abut. Consequently the two members 6 and 7 may be moved toward each other in the direction of their axis with a consequent yield by collapsing movement of the ring 2. Even though said ring is made of cast metal, such as cast iron or steel, it can be collapsed a small amount in the manner described and has sufficient resiliency to exert cushioning reactive effect. When the two members are released the ring expands to its original form and pushes the seat members apart.

The cross sectional form of the ring may vary, so long as it is constructed in a manner to be affected by the coöperating seat members. For example the ring 2^a in Fig. 3 is of circular cross section and with a slight gap at the meeting ends. The seat face 12^a may also be transverse to the axis 85 while all the inclination is on face 12^b as shown.

The cushioning device described is capable of use in a wide variety of structures, particularly where only slight yielding movement of a part or parts is required. It serves admirably for example for use in automobile bearings, for bonnets of valves, for swivel pipe joints and the like. Fig. 4 illustrates the invention applied to a fitting, such as a swivel pipe joint suitable for use in a conduit for steam, water or the like. This fitting also embodies the invention in multiple form. In other words, it illustrates one possibility of including a series 100 of compressible rings in a single joint, thereby increasing the amount of possible relative axial movement between the end members. The fitting described comprises two members 20 and 21 connected together 105 so as to be capable of relative rotation around their common axis. As illustrated member 21 is provided with an annular transverse face 22 forming a shoulder to receive the union nut 23 having threaded connection at 24 to member 20. One of the members 21 and 23, say member 23, carries

a layer 25 of anti-friction metal at the joint. The fitting is also provided with the cushioning means now to be described for holding the parts tightly together at this joint.

5 To exert the proper cushioning effect in the joint member 21 is provided with an annular portion 26 carrying the tapered or conical seat 27, while an extension of member 21 carries a ring 28 having a coöperating 10 tapered or conical seat 29. These seats 27 and 29 may coöperate with a single ring, such as the ring 2 of Fig. 1, but as shown each of said surfaces coöperates with a separate ring 30, and between the two rings 30 is 15 located an idle ring 31. Rings 30 may be of triangular cross section as shown or of round cross section as shown in Fig. 3 and are of course split at one point of their circumference as at 11, Fig. 2. Ring 31, however, 20 is a complete unbroken annulus. To prevent relative rotation of the yielding cushioning parts, such as might produce wear, any suitable means may be provided for preventing rotation between the members 21 and 22 such as the pin or projection 25 32 on member 28 working in a slot or recess in member 21.

With the arrangement described the members 21 and 20 may be relatively moved longitudinally of their axis by turning up the threaded connection 24, which compresses the rings and places them under tension, so that they produce a cushioning or yielding effect. Said rings can be compressed only 35 until the gaps therein are fully closed, as a consequence of which the total yield can be limited to an amount controlled by the size of gap. It is therefore possible to proportion the gaps so that they will be exactly 40 closed when the threaded joint 24 is screwed up tight. In this condition full cushioning effect is exerted to keep the joint at the surface 22 tight. Relative rotation of the parts

is permitted, but relative longitudinal movement is prevented in both directions. 45

The construction described is obviously capable of adaptation for many devices and can be materially modified without departing from the spirit of the invention.

What I claim is:—

1. A cushioning device, comprising a compressible split annulus formed of cast metal, and a coöperating seat member therefor. 50

2. A cushioning device, comprising a compressible split annulus formed of cast metal, an abutment on one side of said annulus, and a coöperating seat member having an annular inclined surface to receive said annulus and located on the other side thereof, whereby said annulus offers yielding resistance 60 toward relative movement toward each other of said seat member and abutment. 65

3. A cushioning device, comprising a compressible split annulus formed of cast metal, and two coöperating seat members provided 70 with annular inclined faces to receive said annulus therebetween, whereby said annulus offers yielding resistance toward relative movement toward each other of said seat member and abutment. 75

4. A cushioning device, comprising two coöperating members having annular seats, and an annular compressible member formed of cast metal lying between said seats. 80

5. A cushioning device, comprising two 75 coöperating seat members, and a plurality of compressible split annular cast metal members therebetween. 85

6. A cushioning device, comprising two coöperating seat members, and a plurality of compressible split annular cast metal members therebetween, each two adjacent annular members being separated by a complete solid ring. 90

In testimony whereof I affix my signature. 87
RICHARD SPRINGBORN.
